XR D 15,429

D15,429

UNITED STATES PATENT OFFICE.

SAMUEL AYRES, OF WORCESTER, MASSACHUSETTS.

DESIGN FOR A CAGE OR DISH.

SPECIFICATION forming part of Design No. 15,429, dated October 7, 1884.

Application filed April 4, 1884. Term of patent 14 years.

To all whom it may concern:

Be it known that I, SAMUEL AYRES, of the city and county of Worcester, State of Massachusetts, have invented a new and useful Design for a Wire Dish or Cage, of which the following is a specification.

My design is fully shown in the accompanying photograph, which shows two views of the same at right angles to each other, or nearly so. Its principal feature consists of an escaloped circle at the top having centrally-converging

rays, the continuation of said rays showing the sides at right angles, or nearly so, after slightly converging, as they leave the ring or base of the escaloped circle.

I claim—

The ornamental design or shape for the dish or cage, substantially as shown and described.

SAM'L AYRES.

Witnesses:

J. G. ARNOLD,
C. H. ARNOLD.
